UNITED STATES PATENT OFFICE.

SAMUEL L. POWELL, OF NEWBERRY, SOUTH CAROLINA.

SHUTTER-WORKER.

SPECIFICATION forming part of Letters Patent No. 632,365, dated September 5, 1899.

Application filed May 31, 1899. Serial No. 718,891. (No model.)

To all whom it may concern:

Be it known that I, SAMUEL L. POWELL, a citizen of the United States, residing at Newberry, in the county of Newberry and State of 5 South Carolina, have invented a certain new and useful Improvement in Shutter-Workers, of which the following is a full, clear, and exact description.

This invention relates to that form of devices for opening and closing to any desired extent the outside shutters or blinds of buildings from within the building and without the necessity of raising the windows.

In carrying out my invention I employ on 15 each shutter a guideway in which is pivoted the shutter-fastener, and this guideway receives an operating-rod which is actuated by novel connections from within the building to release the fastener and then swing the 20 shutter to the desired position and hold it thus against any ordinary atmospheric influences, but susceptible of use as a buffer under extraordinary wind-pressure to allow the shutter to swing without liability of damaging the apparatus or window, all as I will proceed now more particularly to set forth and finally claim.

In the accompanying drawings, illustrating my invention, in the several figures of which 30 like parts are similarly designated, Figure 1 is a sectional elevation of sufficient of a window to illustrate my invention in place and with the shutter standing half open. Fig. 2 is a perspective view of the guideway and one 35 member of the shutter-fastener. Fig. 3 is a plan view showing the guideway in longitudinal section and the operating-rod in place. Fig. 4 is a view similar to Fig. 3, showing a modification. Fig. 5 is a plan view of a 40 bearing-plate for the rod-gear. Fig. 6 is an elevation of one of the bearings for the crank-shaft. Fig. 7 is an elevation of the shutter-fastener with the guideway in cross-section. Fig. 8 is a plan view of the leading end of the 45 operating-rod of Figs. 1, 2, and 3; and Fig. 9 is a similar view of the rod of Fig. 4. Fig. 10 is an elevation of one form of operating crank or handle.

The shutter *a* has applied to its lower portion, without mortising or cutting, the guideway *b*, which comprises the base-flange *b'*, by which it may be secured to the shutter, the

elevated runway *b*², slotted longitudinally, the box *b*³, having its inner side *b*⁴ inclined, the incline or cam *b*⁵, and the housing *b*⁶, in which 55 is pivoted the shutter-fastener lever *c*. This lever *c* has its operating-arm *c'* projecting upwardly into the box *b*³ and between the outer head of the box and the cam *b*⁵. The lever *c* has its heel notched at *c*² to engage the housing *b*⁶ to hold the latch in a position to prevent 60 its end *c*' from falling too far forward to interfere with the movement of the leading end of the operating-rod presently described. The complementary member *d* of the shutter- 65 fastener may be as usual. (See Fig. 7.) The operating-rod *e* has its leading end curved and is provided with a roller or rollers *e'*, as in Fig. 8, and is arranged to travel in the runway. Its other end is adjustably applied to the hub 70 *f* of a gear-wheel *f'* by a set-screw *g*, so as to permit accurate adjustment of parts to adapt them to the shutter to be operated. The gear-wheel *f'* is stepped in a bearing-plate *h*, Figs. 1 and 5, which is fixed to the window-sill, 75 and it meshes with a gear-wheel *i*, which is secured to the squared outer end of a crank-shaft *j*. These gear-wheels are arranged in a housing *k*, which is secured to the window-sill. The shaft *j* has its bearing in a bushing 80 *l*, Figs. 1 and 6, which rotates in a suitable hole in the housing.

The shaft *j* rotates in a hole in the window-sill and projects within the building, where it is supplied with a thrust-collar *m*, which is 85 arranged in a bearing-plate *n*, fastened to the window-facing. A squared portion *o* may be provided near the inner end of this shaft to receive the crank or operating-handle *p*, or this handle may be applied in any of a 90 great variety of ways to rotate the shaft. The inner end of said shaft is screw-threaded at *q* to receive a nut *r*, by which the collar *m* may be drawn up against the plate *n* in order to bind the shaft frictionally against rotation, 95 and thus to secure the parts in adjusted position without the aid of other detents; but obviously this frictional locking of the parts will yield slowly to extraordinary pressure, as in high winds, and permit the slow movement of the parts and without danger of breaking. Of course other forms of locking devices may be substituted for that just described; but I prefer what is shown and de- 100

scribed because of its simplicity and its yielding capability.

Instead of the guideway and operating-rod described I may use a guideway composed of 5 a bent rod s , Fig. 4, in which the cam s' is an added piece. The rod t may be forked at its leading end, Fig. 9, to straddle the rod s , and in such forked end is the roller u .

The operation is as follows: When the apparatus is installed in substantially the manner indicated in Fig. 1 and it is desired to open a closed shutter, the thumb-nut r is slackened and the crank is turned so as to rotate the shaft j and its gear-wheel i and 10 through it the gear-wheel f' , whereby a swinging motion is given to the rod e . When in closed position, this rod e has its leading end and roller contained within the box b^3 in front of the arm c' of the shutter-fastener lever, 15 and said shutter-fastener lever is in locked engagement with the catch d . The continued rotation of the crank imparts a motion to the leading end of the operating-rod in the direction of the arrow, Fig. 3, and so the roller 20 end of the operating-rod forces the end c' of the lever toward the shutter and lifts the said lever out of engagement with the catch, and then, the shutter being free, the pressure 25 upon the operating-rod is exerted upon the cam b^5 and tends to swing open the shutter, and then the leading end of the said operating-rod follows down the runway b^2 until the shutter is arrested at the desired opening, and when the desired opening is effected the 30 nut r is tightened and the parts held or locked in such position. When it is desired to close the shutter, the crank is rotated in the opposite direction, and the leading end of the operating-rod travels in the reverse direction 35 in the runway, and its roller is guided in front of the lever c by means of the cam b^5 and the inclined end of the box b^3 into a position that will admit of the said lever engaging the catch by gravity, the leading end 40 of the operating-rod assuming a correct position for the next operation of opening the shutter.

As already sufficiently indicated, the provision of the hub f to receive the operating-rod adjustably admits of the application of a given standard or size of shutter-worker to shutters of different widths.

A further feature of importance in adapting a given size or standard of apparatus to a 55 variety of windows is the construction of the shaft j with the squared end j' , so that if the window-sill happens to be narrow the said shaft may have its squared end pushed through the gear-wheel i and the bushing l 60 until the crank meets the facing-plate n , and then, if necessary, the projecting end of said shaft may be cut off outside the housing.

It will further appear that the operating mechanism is assembled in or upon the window-sill.

I have shown the housing for the shutter-fastener in Figs. 2 and 3 as made integral

with the guideway, but obviously it may be made separate therefrom.

As shown in Figs. 2 and 3, the box is in the 70 nature of a deflection from the plane of the runway in order to accommodate the operating-rod in its combination with the shutter-fastener, and the same is true of the modification shown in Fig. 4; but my invention is 75 susceptible of use with other forms of shutter-fasteners, and, in fact, may be used without combination with a shutter-fastener, although the convenience of the combination of shutter-worker and shutter-fastener is obvious, and, in fact, is preferred.

Obviously the apparatus described is susceptible of modifications in details of construction and arrangement within the principle of my invention, and I wish to be so understood as claiming my said invention.

What I claim is—

1. A shutter-worker, comprising essentially a guideway adapted to be applied to the surface of the shutter, and consisting of base-flanges, a longitudinally-slotted runway terminating in a box having the near side inclined, a cam-surface in the base of said guideway at the entrance to said box, an operating-rod having the leading end provided with a 90 roller and arranged to travel in said runway, means to actuate said operating-rod, and a shutter-fastener, the movable member of which projects into the said box and is adapted to be released by the movement of the said 100 operating-rod in opening the shutter, substantially as described.

2. A shutter-worker, comprising essentially a guideway having its outer end deflected to form a box, a cam arranged at the entrance 105 end of said box and next to the shutter, an operating-rod having a curved leading end provided with a roller and engaged with said guideway, means to actuate said operating-rod from within a building, and a shutter-fastener having its movable member extending into said box and into the path of movement of the leading end of the operating-rod, substantially as described.

3. A shutter-worker, comprising essentially 115 a guideway, a housing at its outer end, a shutter-fastener lever pivoted in said housing, an operating-rod having its leading end arranged in said guideway and adapted to co-operate with the shutter-fastener to unlock it, and 120 means to actuate said operating-rod, substantially as described.

4. A shutter-worker, comprising essentially 125 a guideway adapted to be applied to the shutter, an operating-rod having one end in engagement with said guideway, gearing adapted to be arranged upon a window-sill and connected with said operating-rod, a shaft for actuating said gearing provided with a thrust-collar, a plate to receive said shaft and thrust-collar and a clamping-nut to hold said shaft against rotation, substantially as described.

5. In a shutter-worker, the combination of an actuating-shaft having a thrust-collar, a

bearing-plate therefor, an operating device for said shaft, a clamping-nut applied to said shaft, gearing actuated by said shaft, and means for connecting said gearing and the 5 shutter, substantially as described.

6. A shutter-worker, comprising essentially a guideway adapted to be applied to the shutter, an operating-rod in engagement with said guideway, means to actuate said rod, and a 10 shutter-fastener arranged adjacent to said

guideway and in the path of movement of the operating-rod and having a notched heel adapted to engage its housing, substantially as described.

In testimony whereof I have hereunto set 15 my hand this 29th day of May, A. D. 1899.

SAMUEL L. POWELL.
